Primary Examiner — Mary Ann Calabrese(74) *Attorney, Agent, or Firm* — Leanne Taveggia Farrell; Westman, Champlin & Kelly, P.A.**CLAIM**

The ornamental design for an in-store marketing sign, as shown and described.

DESCRIPTION

FIG. 1 is a front view of the in-store marketing sign.

FIG. 2 is a left side view of the in-store marketing sign of FIG. 1.

FIG. 3 is a right side view of the in-store marketing sign of FIG. 1.

FIG. 4 is a back view of the in-store marketing sign of FIG. 1.

FIG. 5 is a top view of the in-store marketing sign of FIG. 1; and,

FIG. 6 is a bottom view of the in-store marketing sign of FIG. 1.

The dash-dot-dash lines in FIGS. 1-6 form no part of the claimed design for the in-store marketing sign. The dotted lines in FIGS. 1 and 4 represent scores that do form part of the claimed design for the in-store marketing sign.
